* cited by examiner

Primary Examiner — Karen E Eldridge Powers(57) **CLAIM**

I claim the ornamental design for a rain hat, as shown and described.

DESCRIPTION

FIG. 1 is a front perspective view of a rain hat showing my new design;

FIG. 2 is a rear perspective view thereof;

FIG. 3 is a side elevation view thereof;

FIG. 4 is a top plan view thereof; and,

FIG. 5 is a perspective view thereof.

The broken lines showing a partial human figure in FIG. 5 illustrate the environment in which the design is used, and assist showing how the claimed design appears when worn. The broken-line subject matter on the rain hat itself illustrates stitching, and is part of the claimed design.
